**ELECTROSENSITIVE PRINTING APPARATUS
WITH PRINT HEAD CONTINUOUSLY
MOVED ACROSS PAPER**

Zaven Yazejian, Mahopac, N.Y., and Jerome R. Fuld, Trumbull, and Walter V. Benkler, East Norwalk, Conn., assignors to Sperry Rand Corporation, New York, N.Y., a corporation of Delaware
Filed April 30, 1965, Ser. No. 452,273
16 Claims. (Cl. 197—1)

The invention relates in general to printing apparatus and more particularly to an apparatus for printing data electrically or electro-sensitive record material.

Certain known printing arrangements provide a plurality of styli in a patterned arrangement capable of producing characters through selective time energization of the styli as the printer is swept across the face of the record material. The styli are physically separated and electrically isolated from each other in a pattern most conducive to the generation of the desired characters.

In such systems the styli rest directly upon the record material and current is caused to pass from the selected styli through the record material to a ground plate located at the opposite side of the record material, or from one styli through the paper to another styli. The current in passing through the record material causes distinct marks or dots which can be combined through proper timed energization of the styli to form the data to be printed.

The present invention provides a print head drive mechanism for use with such a styli printing arrangement and serves to drive the print head across the record paper in a carefully timed and synchronized manner so as to insure proper printing of output data and to effect control in a completely automatic manner of the print operation.

It is therefore an object of the instant invention to provide a print head drive mechanism for use with a printing arrangement of the type described capable of effecting accurately timed reciprocation of an electronic print head across the surface of a record paper.

It is a further object of the instant invention to provide a print head drive mechanism for use in a printer of the type described capable of providing automatic control of the printing operation including carefully timed reciprocation and return of the print head and automatic retraction thereof during the return excursion.

It is still a further object of the instant invention to provide a print head drive mechanism capable of driving the print head across the record paper and effecting return thereof to the start position automatically in response to print head position.

It is still another object of the instant invention to provide a print head drive mechanism for use with a printer of the type described wherein both automatic and manual control for positioning of the print head and other elements of the printer mechanism are provided.

The many objects and advantages of the instant invention can be seen from the above discussion, and will be further clarified by the following description when taken in conjunction with the accompanying drawings wherein:

FIGURE 1 is a simplified schematic view in perspective of portions of a printer in accordance with the invention;

FIGURE 2 is a simplified schematic view greatly enlarged of the printing head of FIGURE 1, showing the configuration of the styli matrix;

FIGURE 16 is a detail front view of the print head drive control illustrated in FIG. 14.

Referring now to the drawings for a detailed description of the present invention, and more specifically to FIG. 1, a stylus or printing head, generally designated by reference numeral 334 is slidably mounted on a guide rod 336 for movement transversely of record paper 330, or the like at the printing position. Printing head 334

may be driven by any suitable means from a starting point at the left edge of record paper 330, the initial printing position, to the right edge of the paper during the printing cycle, and then back to the left edge, in preparation for printing the next line. Such driven movement is effected at a substantially constant speed by the printing head conveying mechanism of the invention to be described in detail hereinafter, which transmits driven motion to printing head 334 by means of a timing belt 338 attached by fasteners 340 to printing head 334. It is to be understood that incident to printing head 334 being returned to its initial printing position at the end of a printing cycle, roller 332 of the record paper conveyor moves tape 330 in the direction of the directional arrow *a* to place the next printing line of paper 330 into printing position.

Printing head 334 is formed of an electrically non-conductive material and is provided in the illustrated embodiment with sixteen individual styli assemblies 342 (FIGURE 3), each having a stylus or electrode in the form of a rod-like pin 344. The pins are designated P1 through P16 (FIGURE 2) to differentiate the pins from one another. Styli pins 344 (FIGURE 3) protrude from the bottom of printing head 334, fourteen of which pins (P1—P14) are arranged into a matrix having the con-

60
65

figuration of a digit "8" slightly slanted to the left, as seen in the bottom view of the printing head 334, shown at FIGURE 2. In addition a pair of pins, P15 and P16, are provided for inserting the decimal point designation in the proper position between numerals along the line of print.

The pin 344 of each stylus assembly 342 is formed of conductive material, preferably of tungsten and is slidably disposed in an associated pin hole or channel 348 defined in a bottom portion 352 of printing head 334. Each pin 344 is provided with a sleeve 354 of conductive material, such as stainless steel, which sleeve is "press fit" onto the upper end of the pin. Sleeve 354 is slidably confined in a channel 356 aligned with channel 348 and defined in an intermediate portion 358 of printing head 334 to permit up and down movement of pin 344 and sleeve 354 in channel 356. A biasing spring 362 of the coil type and of conductive material is provided for each pin 344 and is loosely disposed under compression in the channel 356 provided for its associated pin. Spring 362 presses against sleeve 354 of its associated pin 344, biasing the pin downward to maintain the free or lower end of the pin in constant contact with the upper surface of record paper 330. Downward movement of pin 344 is limited by its sleeve 354 abutting a shoulder 364 formed by printing head portion 352 where channel 348 joins channel 356.

An electrical connecting lead 366 is provided for each pin 344 and extends through a hole 368 defined in a portion 370 of printing head 334. Each lead 366 enters the channel 356 of its respective pin 344 and is connected electrically to the uppermost portion of the spring 362 in such channel. The leads 366 serve to connect their respective pins 344 (P1-P16) to the pin energizing circuits.

It may be noted that with the described mounting arrangement of each stylus assembly 342, each stylus pin 344 is individually spring biased to continually bear upon and frictionally engage the top surface of record paper 330, as printing head 334 is driven transversely of the tape. Such individual spring biasing automatically compensates for unevenness of the tape surface and for variation in the wear rates of the individual stylus pins 344. However, this direct contact of the stylus pins with the paper surface has a tendency, should the stylus pins be exposed from the print head, to pick up fibers from the paper, dust particles and other foreign matter which shortly will cause a fouling of the print head considerably reducing, if not altogether disrupting, the print capability of the arrangement.

As a result of the difficulties with fouling of the print head, a boot 350 is positioned over the print head as seen in FIG. 4, which boot consists of a cap 351 made from phenolic or similar material and a gasket 353, made from a thermoplastic resin such as that which is commonly known and sold under the trademark Teflon. The boot 350 is provided with a plurality of holes, each in substantially alignment with one of the stylus pins of the printing head so that the individually spring biased stylus pins may protrude through the boot and contact the recording surface of paper 330.

The boot 350 is spring loaded with respect to the print head by springs 380 (one shown) recessed in channels or grooves 381 in the cap 351. The springs 380 act upon pins 382 in contact with the collar 384 surrounding the print head. The bias provided by springs 380 forces the Teflon gasket 353 against the surface of record paper 330 so that the stylus pins 344 are completely isolated except for the cross-sectional ends which contact the surface of the tape.

Since the Teflon gasket is in pressure contact with record paper 330 when the print head assembly is in the print position, the end of the cap and Teflon gasket have a radius comparable to that of the roller 332 so as to insure good contact between the gasket and the paper

over the full gasket area. The holes in the cap 350 through which the print pins pass have a dimension only slightly larger than the pins themselves; however, due to the natural lubrication provided by the Teflon material, the pins may very easily slide in and out of the print head in response to pressure by the springs 362 insuring good contact between the pins 344 and the surface of record paper 330.

While the boot 350 is shown as being formed of two separate elements 351 and 353, it is within the purview of the invention to provide the entire boot of a single material such as fluorocarbon resin with a filler so as to combine the low friction and high dielectric properties of Teflon with low wear and rigidity. In addition, gasket 353 may be made from other materials having properties similar to Teflon.

When the print head is released to the print position, the outer surface 355 of bottom portion 352 (FIGURE 3) is stopped before engaging inside surface 356 of the cap 351 by a stop 385 (FIGURE 4) on the cap cooperating with suitable means (not shown) so that a gap 357 is provided therebetween. The individually biased stylus pins 344 protrude slidably through the boot 350 to engage the record surface 330. The spring bias on the boot relative to the print head places the front surface of the Teflon gasket 353 firmly but resiliently against the record surface to be printed upon. Thus, the stylus pins 344 are completely surrounded by the boot 350 so that only the cross-sectional end surfaces of the pins are exposed and these firmly contact the surface of paper 330. In this position, the record sheet engaging ends of the pins are substantially in the same plane as the outer surface of the Teflon gasket 353.

With such an arrangement, the gasket 353 which follows the record sheet curvature is maintained firmly against the record surface as it and the print head are driven transversely of the record sheet. The Teflon sheet biased against the record surface eliminates the gap which was heretofore present between the print head and the record sheet and in which dust particles accumulated, fouling the pins.

In addition to the elimination of such gap, and the relatively tight fit of the pins as they pass through the Teflon gasket, the gasket effectively mashes the exploded dust particles of the record sheet surface back into the sheet surface such that no noticeable loose dust particles are formed to foul the pins. This wiping action of the Teflon gasket as it moves across the record surface under pressure forcing the dust particles back into the surface impregnates the surface with all loose particles preventing these particles from entering the pin channels in the print head and from generally fouling the stylus or other portions of the printing arrangement.

In addition to solving the fouling problem, as indicated above, the provision of the boot 350 over the print head provides an added support for the stylus pins over substantially their entire length to the very ends which contact the record surface of paper 330 resulting in an increased stability and more accurate registration of the pins so that greater clarity in printing is achieved and scratching of the surface due to vibrations in the pin is completely eliminated.

By selectively electrically pulsing certain combinations of pins 344 of the stylus matrix of FIG. 2, the configurations of numerals 0 through 9 and some special symbols may be printed upon record paper 330 (FIG. 1), as printing head 334 is moved transversely thereto. Such marking is effected in the preferred embodiment by causing a succession of current pulses to flow from one pin 344 (FIG. 3) along the chemically coated surface of conductive record paper 330 to a second pin 344 which is associated with and spaced from the first pin. For example, with the pair of pins P1, P2 shown in FIG. 3, a pulse of current may be caused to flow successively from P1 along record paper 330 to pin P2. Such current flow causes

chemically treated tape 330 to darken or change color at the two points where pins P1 and P2 engage the tape surface to provide legible distinct marks thereat, which due to successive pulsations thereof may take the form of elongated dots or lines.

The electrical pulsing of the pins is substantially instantaneous, such that movement of printing head 334 relative to record paper 330 is effectively stopped during relative motion between pin 344 and record paper 330 during the printing.

The sixteen styli pins 334 (P1-P14, FIG. 2) comprising the digit "8" styli matrix and a decimal point designation as mentioned above, are electrically connected to the pin energizing circuits in pairs.

The pin styli 344 are therefore divided into pin pairs and an electrical styli energizing circuit (FIGURE 5) is provided for each pair of pins. Thus, eight pin energizing circuits, or "driving" circuits 371-378 are utilized for energizing the sixteen pins. The digits 0 and 1 through 9, plus certain symbols, such as the letter "C" and the decimal point may be printed by causing the driving circuits to successively energize selective pin pair combinations in accordance with a particular time sequence.

The driving circuits utilize means in the form of a decoding matrix 383 for detecting the input of certain "pin selection" signals derived from an input processor. The decoding matrix translates the selection signals and conditions the driving circuits to effect subsequent energization of associated pin pairs, or to prevent such energization, as to the signals dictate. The detecting means also automatically and continually responds to changes in pin selection as denoted by the selection signals.

A "print" signal causes energization of print initiating means (not shown) which generate initiating or gating signals which are applied simultaneously to all driving circuits via the decoding matrix 383. This causes the driving circuits of the selected pin pair combination to be simultaneously energized to form the desired character on the record medium, while those of the unselected pin pairs are maintained unenergized in accordance with the preconditioned state of the driving circuits. The print initiating signals are in the form of electrical pulses.

During printing, the printing head 334 is moved at a substantially constant speed transversely of the record paper 330. Selection of the pin pairs to be energized and pulsing of their respective driving circuits are synchronized with transverse movement of the print head such that desired characters are printed sequentially on a print line. In this way, energization of selected pin pairs in response to the common print initiating pulses will be sufficiently instantaneous so as to appear to "stop" relative motion between the print head and record material, producing distinct printed characters on the record material, notwithstanding such relative motion.

Such an arrangement obviates the need to use a "ground" plate required in some systems, and minimizes the amount of equipment required for proper operation. The simultaneous energization of selected pin pairs by the common print initiating signals to print a character on the record medium also provides a highly reliable printing arrangement at minimal cost.

The print head drive mechanism of the instant invention as seen in FIGS. 6 and 7, includes the print head 334 mounted on guide shaft 336 for sliding movement along the shaft length from the extreme left hand margin to the extreme right hand margin of the record paper 330. The guide shaft 336 for the print head is secured eccentrically of a pair of rotatable discs 501 and 502, seen most clearly in FIG. 8, by suitable fastening means, e.g., screw 504. The eccentric relationship between shaft 336 and disc 502 is also shown in FIG. 12. The discs 501 and 502 are rotatably mounted in suitable apertures in brackets 510 and 512, secured respectively to side support plates 514 and 516 of the printer mechanism. FIG. 16

shows in detail disc 501 in registration with the aperture in bracket 510.

A platen or paper roller 332 is secured to shaft 506 (FIG. 8) by suitable means, such as set screws 508, which shaft 506 is rotatably supported in the side support plates 514 and 516. The paper 330 is held against the platen 332 by three sets of pressure rollers 518, 520 and 522, all of which are shown in the FIG. 7 top view. The two sets of rollers 518 and 520 each consist of pairs of individual rollers mounted on respective stud shafts 519 and 521, guided in slots 517 and 523 (FIGS. 9 and 10) in the side support plates 514 and 516. The rollers 518 and 520 are spring biased into pressure contact with the platen 332 by springs 523 and 525 (FIG. 7) secured to a common pin 515 one each of which is fastened to the side support plates 514 and 516. The rollers 522 are mounted on a spring loaded shaft 526 guided in slots 527 in the side support plates 514 and 516. The shaft 526 is spring loaded to pins (not shown) secured to the side support plates 514 and 516 by means of springs 528 (FIG. 10).

The pressure rollers 518 also support a transparent tear bar assembly consisting of a tear bar 531 (shown in FIGS. 6 and 9 only for purposes of clarity) supported by suitable bracket 532 on the stub shafts 519 of the pressure rollers.

In order to retract the pressure roller sets 518, 520 and 522 from the surface of the platen 332, for example during paper insertion, a lever 530 and actuating bar 537 are provided inter-connecting a pair of cams 535 (FIG. 11) and 536 (FIG. 9) mounted on the platen support shaft 506 on either side of the platen 332, such that cam surfaces on the cams 535 and 536 contact the shafts 519, 521 and 526 of the three pressure roller sets and force the rollers outwardly from the platen 332 in response to clockwise rotation (direction arrow "b") of the cams by the lever 530, as seen in phantom line in FIG. 11.

The paper support bar 529 which extends between the side support plates 514 and 516 also serves as an abutment for the lever 530 determining the starting position thereof. The springs biasing the various bars associated with each of the sets of pressure rollers serve to naturally force the lever 530 against the paper support bar 529 unless pressure is applied thereto, to oppose the natural bias of these springs.

A paper feed guide 539, seen most clearly in FIG. 9, is positioned beneath the platen 332 and supported by the side support plates 514 and 516. The guide 539 serves the well known purpose of maintaining the paper against the bottom side of the platen 332 and guides the paper upwardly between the print head 334 and the platen. In order to accommodate the pressure rollers 520 and 522 the guide 539 is provided with suitable apertures through which the rollers may extend to press the paper against the platen.

The above-described combination including the platen, sets of pressure rollers, paper tear and support bars and the paper guide, are common printer and typewriter elements which may obviously be provided in a form different from that described and illustrated herein. In addition, other means for supporting these members with relation to one another may be provided in accordance with well-known conventional techniques without departing from the spirit and scope of the instant invention which relates more specifically to the means described herein-after for effecting drive of the print head across the record paper and control thereof in accordance with requirements for effecting proper printing. A means for retracting the pressure rollers other than the specific cams 535 and 536 may also be provided; however, as will be seen hereinafter, these cams in combination with other control elements of the system make possible a simplified control of the print head and pressure roller sets during operation of the printing mechanism.

Looking more closely to the construction of the print head 334, as seen in FIGS. 6, 8 and 9, the pin carrying

portion 540 of the print head forms an integral print head construction with the cylindrical body member 541. The print head 334 is mounted to the guide bushing assembly 545 by flanges 542 on the print head secured to an upright flange 543 forming part of the bushing assembly.

The bushing assembly is formed primarily of hollow housing member 546 (FIG. 8) which surrounds the guide shaft 336 and is spaced therefrom by a pair of tubular bushings 547 made preferably of a synthetic material such as Teflon or any other known self-lubricating material suitable for serving as a bearing means between the housing member 546 and the guide shaft 336. A thin jacket or casing 548 almost completely surrounds the assembly 545 providing the flange 543 and insuring that the elements of the assembly are maintained in proper position.

The print head 334 and guide bushing assembly 545 are freely rotatably mounted on the guide shaft 336 and are maintained in proper upright position with respect to the platen 332 by a slide bar 550 riding in a slot 551 provided in a longitudinally extending guide member 552 positioned beneath the platen 332, as illustrated in FIG. 9. The guide bar 552 extends at least between the limits of print head scan and serves to maintain the print head 334 in a proper upright position at all times. The slide bar 550 is provided at its extreme end with a bushing member 553 which rides on the inner surface of the channel 551 maintaining the end of the slide bar 550 at a proper distance from the channel and facilitating the sliding movement thereof.

The slide bar 550 is secured to the bottom of the guide bushing assembly 545 by means of screws or other suitable fastening means secured through the slide bar 550 and into the housing member 546 and the tubular guide bearings 547, thereby not only fastening the slide bar to the bushing assembly 545 but also serving as a key preventing relative rotation between the guide bushings 547 and the housing member 546.

The guide bushing assembly 545 is clamped to the timing belt 338 by means of a clamp formed by opposed clamping jaws 555 and 556 clamped to the belt by means of screws 340. The clamp is secured to the guide bearing assembly 545 by means of opposed projections 557 formed on the clamping jaw 555 and interlocking with corresponding projections 558 on the housing member 546 thereby locking the clamp to the bushing assembly. In order to prevent slippage between the timing belt 338 and the print head and guide bushing assemblies, a toothed belt is provided and the clamping jaw 556 is provided with a surface corresponding to the configuration of the timing belt teeth, so that a positive locking between the clamp and the timing belt is effected, thereby eliminating all possibility of slippage during movement of the print head assembly.

The print head may be manually retracted from its normal position with the energizing pins in contact with the surface of the record paper for any purpose by means of a manually operated lever 560 secured to the center shaft 561 of the rotatable disc 501. As indicated previously, the guide shaft 336, upon which the print head assembly is mounted for sliding movement, is eccentrically secured to the rotatable discs 501 and 502 such that rotation of the discs will effect a transverse displacement of the guide shaft 336, and consequently also the print head 334, in a direction substantially perpendicular to the surface of the platen 332. This action is seen most effectively in FIG. 13 which has been simplified for purposes of clarity. Clockwise rotation of the lever 560 (direction arrow "c") from its vertical rest position will effect a clockwise rotation of the guide shaft 336 about the center line of the rotatable discs 501 and 502, thereby displacing the guide shaft and the print head assembly 534 in a direction away from the platen 332. Since the guide bearing assembly is freely rotatable upon the guide

shaft 336, the print head 334 will not rotate with the lever 560 but will be maintained in its normal upright position (phantom outline) by the slide bar 550 riding in the slot 551.

5 In FIG. 10, it can be seen that the manual lever 560 is retained in its rest position by an adjustable stop 562 and is biased into this rest position against the stop 562 by a spring 563 connected between a pin 564 on the lever 560 and a pin 559 connected to the side support plate 514. As will be indicated hereinafter in greater detail, it is necessary that the print head be automatically retracted when it reaches the end of its scan so that the energizing pins on the print head are not in contact with the paper surface when the print head is reciprocated back to its starting position. This is accomplished automatically within the machine and thus the lever 560 is normally utilized only when the printer is not in use.

For purposes of replacing the paper roll 538 and inserting the paper strip beneath and around the platen 332 20 and between the print head and the platen it is necessary not only to retract the pressure rollers but also to simultaneously retract the print head assembly. For this purpose, a pin 565 (FIGS. 6 and 14) is carried by the cam 535 and is secured to an operating lever 566 operatively 25 connected to control lever 567 by means of a pin 568 carried by the lever 566 riding in a slot 569 in the control lever 567. The control lever 567 is also provided with an ear 570 which contacts the stop 562 determining the rest or neutral position of the control lever.

30 The control lever 567 is directly connected to the rotatable disc 501, as seen in FIG. 16, and is normally biased into its rest position with the ear 570 against the stop 562 by the spring 563 (FIG. 10) connected to the manual control lever 560. The control lever 560 being 35 secured to the center shaft 561 for the rotatable disc 501, the spring 563 determines the neutral or rest position for the lever 560 and the control lever 567, in turn properly positioning the print head with respect to the platen 332.

When it is necessary to retract the pressure rollers on 40 the platen 332 in the print head assembly 334, such as when a new paper strip roll is to be inserted into the machine, rotation of the lever 530, as seen in FIG. 14, in a clockwise direction will effect a rotation of the cams 535 and 536 thereby forcing the three sets of pressure rollers 45 outwardly away from the platen 332 and will simultaneously actuate the lever 566 by way of the pin 565 rotating the control lever 567 in a clockwise direction against the normal bias of spring 563 and away from the stop 562, thereby displacing the guide shaft 336 and the 50 print head 334 in a direction away from the platen 332. When the lever 530 is rotated back to its initial position in the counter clockwise direction, the spring 563 will effect a return of the guide shaft 336 through the disc 501, control lever 567, shaft 561 and manual lever 560.

55 The platen 332 is rotated during normal machine operation to effect advance of the paper 330 automatically by means of a spring clutch 572 located on the left side of the printer mechanism, as seen in FIGS. 6-8, which spring clutch 572 is actuated in the well-known manner by a suitable control linkage (FIG. 7). The automatic paper advance mechanism does not form a specific part of the instant invention and may be provided in accordance with any conventional paper advance mechanism construction capable of effecting rotation of the platen 332 either automatically or in response to control from the keyboard or other control portion of the printer.

Single line paper advance may also be performed manually by rotation of the manual paper advance handle 26 located at the right side of the printer, as seen in FIG. 8, 70 which handle drives the platen via a unidirectional spring clutch. The operation of the lever 26 provides a forward advance of the paper equivalent to one printing line, and the spring clutch 574 slips when the lever is moved in a counter-clockwise direction to the initial position in preparation for a forward advance.

The print head 334 is driven by means of the endless toothed belt 338 looped around a driving pulley 580 and a driven pulley 581. As seen in FIG. 10, the pulley 581 is driven by means of a motor 582 mounted on the frame 500 of the printer. It should be noted that even though pulley 581 is referred to as a driven pulley it functions as a driving pulley when considering its relationship to belt 338. The driving function of pulley 580 is discussed hereinbelow. Drive is obtained from the motor 582 via reduction gears 583 and 584 which effect rotation of drive shaft 585, supported by U-shaped support bracket 586 also mounted on the frame 500 of the printer. The drive from shaft 585 is once again applied through suitable reduction gears 587 and 588 to a drive shaft 589 which is supported, as seen in FIGS. 10 and 15, by a second U-shaped bracket 590 mounted on the frame 500. The shaft 589 is supported on the frame 590 at the forward end thereof adjacent the pulley 581 by a suitable bushing 591 and at the rear portion of the mechanism by a sleeve 592 keyed to the shaft 589 and supported within a guide bearing 593. The sleeve 592 extends beyond the bearing 593 toward the pulley 581 and is provided with a pair of collars 594 and 595 which serve to maintain the proper position of the sleeve 592 and the shaft 589, and prevent axial shifting thereof.

The pulley 581 is mounted upon the drive shaft 589 on suitable bushings 596 and 597 so that the pulley 581 may freely rotate regardless of the drive provided by the shaft 589. An extension 598 on the pulley 581 abuts with the sleeve 592 and has a diameter substantially identical to this portion of the sleeve 592. A clutch spring 600 is positioned over both the sleeve 592 and the extension 598 of the pulley 581 with one end of the spring secured at 599 to the sleeve 592. As a result of the clutch spring 600, drive from the drive shaft 589 may be applied to the pulley 581 through the sleeve 592 by actuating the clutch spring 600 thereby effecting a connection between the sleeve 592 and the extension 598 of the pulley 581.

The spring 600 is wound upon the sleeve 592 and the extension 598 of pulley 581 such that normal rotation provided by the drive shaft 589 will result in a tightening of the spring locking the sleeve 592 to the pulley 581 so long as some means is provided for holding the free end of the spring coil. It is therefore possible to activate and deactivate the spring clutch applying driving power and withdrawing driving power, respectively, from the pulley 581 by controlling the free end of the clutch spring 600.

The clutch interconnecting the drive shaft 589 and the pulley 581 is engaged by pressing a nylon shoe 601 (FIGS. 15 and 16) against the outside diameter of the free end of spring 600 thereby effectively holding or locking the free end of the spring causing the spring to tighten up and locking the sleeve 592 to the pulley 581. The nylon shoe 601 is mounted on the end of a spring loaded lever 602 pivoted at 603 to a frame member 604 of the machine. The lever 602 is biased by spring 605 interconnected between the levers 602 and a pin 606 mounted on the frame of the machine, so as to be biased in the direction of the spring 600. A latching lever 607 is pivoted at 608 to the frame member 604 of the machine and is provided with a hook portion 609 which engages with a latch 610 on the lever 602, normally holding the lever 602 against the bias of spring 605 and preventing the shoe 601 from contacting the clutch spring 600.

The latching lever 607 is normally biased in the clockwise direction by a spring 611 interconnected between the lever 607 and a pivot pin 612 fastened to the plate 604 of the machine. The end of the locking lever 607 opposite the hook shaped end 609 communicates with an electromagnet 615 which when energized, attracts the lever 607 causing counter-clockwise rotation thereof against the bias of spring 611 disengaging the hook shaped member 609 from the latch portion 610 on the lever 602.

The lever 602 is also provided with a cam follower 616 which communicates with a cam portion 617 on a plate 76

618 secured to the inside surface of the pulley 581. Contact between the cam surface 617 and the follower 616 effects a counter-clockwise rotation of the lever 602 about the pivot shaft 603 against the bias of spring 605.

5 It can therefore be seen that the print operation is initiated by energization of the electromagnet 615 which attracts the locking lever 607 causing counter-clockwise rotation thereof against the bias of spring 611. As a result of the counter-clockwise rotation of latching lever 607, the hook-shaped end 609 disengages from the latching portion 610 of the lever 602 and spring 605 will rotate the lever 602 in a clockwise direction about the pivot shaft 603 urging the shoe 601 into contact with the clutch spring 600. The constantly rotating shaft 589 will then transfer 10 its driving force through the sleeve 592 and the spring clutch 599 to the pulley 581 thereby driving the print head 334 through the timing belt 338.

The print head begins its scan at the extreme left hand position of the guide shaft 336 and moves along the length 20 of the guide shaft across the width of the paper 330. The driving pulley 581 is dimensioned so that one complete revolution of the pulley will effect a reciprocation of the print head 334 from its extreme left hand position to its extreme right hand position. By then positioning the cam surface 617 at a proper point along the circumference of the drive pulley 581, when the print head 334 reaches its extreme right hand position, the cam surface 617 will contact the follower 616 forcing the lever 602 to rotate in a counter-clockwise direction disengaging the shoe 601 from the spring 600. The lever 602 is rotated a distance sufficient to re-engage the latch portion 610 with the U-shaped portion 609 on the latching lever 607 and since the electromagnet 615 is no longer activated, the shoe 601 will be retained in this inactive position until the next print cycle 35 is required.

As soon as the shoe 601 is disengaged from the clutch spring 600, the pulley 581 will be automatically disengaged from the drive shaft 589. At this point, a clock spring (not shown) within the driving pulley 580, which 40 has been wound during the initial scan of the print head, will serve as a means for driving the pulley 580 and the pulley 581 reciprocating the print head 334 back to its initial position.

The pulley 580 is also provided with a detent 619, seen 45 in FIG. 6, within which a follower 620 carried by a lever 621 pivoted at 622 to the machine frame is biased so that the follower 620 is normally urged into the detent 619 by a spring 623, interconnected between the lever 621 and a pin 624 on the machine frame. This combination serves to determine the initial or start position of the print head more accurately since in returning the print head to the start position, the pulley 580 will substantially completely lose the driving force from the spring therein as the print head reaches the start position at the extreme left 55 of the guide shaft 336, and at this time the follower 620 will drop into the detent 619 holding the pulley 580 in this position. By this means, the start position for the print head is accurately determined at all times thereby insuring proper registration of the data that is printed 60 since this registration is dependent upon the accurately time positioning of the print head after initiation of the print operation through energization of the electromagnet 615.

As seen in FIG. 8, a stop member 625 and spring 626 65 are positioned at the extreme left end of the guide shaft 336 to help determine the start position of the print head arrangement and cushion the arrival of the print head at this position during the return excursion.

As indicated previously, it is necessary during return of 70 the print head at the end of print scan to retract the print head so that the energizing pins do not rest upon the record paper during return movement of the print head. The invention therefore provides a means for automatically retracting the print head when it reaches the end of the print scan and automatically returns the print head to

the surface of the record paper as soon as the print head reaches the start position.

The print head retracting mechanism is illustrated in FIGS. 14-16. A lever 628 (also shown in FIG. 6) is loosely mounted at one end of pivot lever 629, which is rotatable about the pivot shaft 612 mounted on the frame 604 of the machine. The lever 628, as seen in FIGS. 15 and 16, is provided with an ear 631 which limits clockwise rotation of the lever 628 on the lever 629 and is connected via a spring 632 to a similar ear 633 on the lever 629. As a result of the bias provided by spring 632 the lever 628 is normally retained in a position with the ear 631 in contact with an edge of the lever 629.

A lever 635 is rigidly secured to the lever 629 between the pivot shaft 612 and the end carrying the lever 628 such that clockwise rotation of the lever 629 will result in a downward movement of the free end of lever 635 to which is connected an actuating lever 636 by suitable fastening means 637. The lever 636, as seen in FIG. 14, is connected to the control lever 567 by means of a pin 638 riding in a slot 639. Downward movement (arrow "d") of the lever 636 effects a clockwise rotation of the control lever 567 until the projection 640 on the lever 567 overrides the lip 641 on a latching lever 642 thereby locking the control lever 567 in the rotated position. As indicated above, clockwise rotation of the control lever 567 effects a clockwise rotation of the rotatable disc 501 connected eccentrically to the guide shaft 336, which in turn effects a retracting of the print head.

The above-described print head retract mechanism operates in the following manner. As the print head reaches the extreme right-hand position of the print head scan, an extension 645 (FIG. 16) on the clamp member 556 on the print head guide assembly will strike the lever 628 rotating the pivot lever 629 in a clockwise direction. It should be noted at this point that should the print head pass beyond the control lever 628 by any means, it can pass back over the control lever 628 against the bias of spring 632 without effecting the position of lever 629 during the return movement of the print head.

With the lever 629 rotated in the clockwise direction, swinging the end of lever 635 in a downward direction, and actuating the control lever 636, the control lever 567 will be rotated in a clockwise direction and latched by latching lever 642 holding the print head in the retracted position during the entire return excursion thereof. As the print head reaches the start position during return movement thereof, a cam surface 650 (FIG. 14) on the drive pulley 581 will contact the locking lever 642 forcing it away from the control lever 567 until the projections and extensions 640 and 641 disengage permitting the spring 563 connected to the manual control lever 560 to rotate the control lever 567 in the counter-clockwise direction until the ear 570 contacts the stop 562, thereby repositioning the print head adjacent to the paper in the start position.

Electrical energization of the print head is accomplished through the individual cables 660 (FIG. 7) from the printer matrix, which cables 660 are maintained in proper position during print head reciprocation by a cable support and guide member 661 which is rotatably mounted to a frame member in the machine. The guided support member 661 serves as a means for maintaining the cables in alignment and providing sufficient slack so as to prevent undue tension on the cables during reciprocation of the print head.

Although a specific embodiment of the invention has been illustrated and described in detail by way of example, it is to be understood that the invention is not limited thereto. Various changes may be made in the design and arrangement of parts without departing from the spirit and scope of the invention as defined by the appended claims as will now be understood by those skilled in the art.

We claim:

1. In a printer for printing electrically on electro-sensitive record material by means of a print head traversing said record material in a continuous movement in a reciprocating manner,

print head means including a print head,

guide shaft means for supporting said print head adjacent said record material for reciprocal movement thereof across the width of said material, driving means for driving said print head from one end of said guide shaft means to the other at an essentially constant rate,

motor means for energizing said driving means, clutch means and actuating means therefor for connecting said motor means to said driving means in response to a control signal, said clutch means comprising a shaft driven by said motor means, a first hub affixed to said shaft, a second hub rotatably mounted on said shaft, and means responsive to said actuating means for coupling said first and second hubs for conjoint rotation about said shaft under conditions where said driving means is driving said print head, means for deactivating said clutch means automatically in response to said print head being moved to and occupying said other end of said guide shaft means, said deactivating means operatively connected to said responsive means to decouple said hubs regardless of shaft rotation.

2. In a printer as set forth in claim 1 wherein said guide shaft means is mounted eccentrically for movement with respect to said record material in response to rotation thereof, and including control means for automatically moving said guide shaft means away from said record material in response to said print head being moved to and occupying said other end of said guide shaft means.

3. In a printer for printing electrically on electro-sensitive record material by means of a print head traversing said record material in a continuous movement in a reciprocating manner,

print head means including a print head, guide shaft means for supporting said print head adjacent said record material for movement thereof across the width of said material, driving means for driving said print head from one end of said guide shaft means to the other at an essentially constant rate,

motor means for energizing said driving means, and a spring clutch and actuating means therefor for connecting said motor means to said driving means in response to a control signal,

said driving means including guide belt means secured to said print head and pulley means operatively supporting said guide belt means for rotation, said driving means further including means for biasing said pulley means and said print head into a neutral position under conditions where said driving means is not driving said print head, said print head being disposed at said one end of said guide shaft means when said neutral position is effected.

4. In a printer for printing electrically on electro-sensitive record material by means of a print head traversing said record material in a continuous movement in a reciprocating manner,

print head means including a print head, guide shaft means for supporting said print head adjacent said record material for movement thereof across the width of said material, driving means for driving said print head from one end of said guide shaft means to the other at an essentially constant rate,

motor means for energizing said driving means, clutch means and actuating means therefor for connecting said motor means to said driving means in response to a control signal,

13

said clutch means including a driven element, a driving element coupled to said driving means and concentric with said driven element, a spring element secured to said driven element and encompassing a portion of said driving element, and means for selectively fixing said spring element with respect to said driving element in response to said actuating means.

5. In a printer as set forth in claim 4 wherein said actuating means includes electromagnet means for actuating said means for selectively fixing said spring element.

6. In a printer for printing electrically on electro-sensitive record material by means of a print head traversing said record material in a continuous movement in a reciprocating manner,

print head means including a print head, guide shaft means for supporting said print head adjacent said record material for movement thereof across the width of said material, driving means for driving said print head from one end of said guide shaft means to the other at an essentially constant rate,

motor means for energizing said driving means, clutch means and actuating means therefor for connecting said motor means to said driving means in response to a control signal,

means for deactivating said clutch means automatically in response to said print head being moved to and occupying said other end of said guide shaft means, said clutch means including a driven element, a driving element coupled to said driving means and concentric with said driven element, a spring element secured to said driven element and encompassing a portion of said driving element, and means for selectively fixing said spring element with respect to said driving element in response to said actuating means, said actuating means including electromagnet means for actuating said means for selectively fixing said spring element,

40 said means for deactivating said clutch means including cam means secured to said driving element for deactivating said means for selectively fixing said spring element.

7. In a printer for printing electrically on electro-sensitive record material by means of a print head traversing said record material in a continuous movement in a reciprocating manner,

print head means including a print head, guide shaft means for supporting said print head adjacent said record material for movement thereof across the width of said material, driving means for driving said print head from one end of said guide shaft means to the other at an essentially constant rate,

motor means for energizing said driving means, clutch means and actuating means therefor for connecting said motor means to said driving means in response to a control signal,

55 said guide shaft means being mounted eccentrically for movement with respect to said record material in response to rotation thereof, control means for automatically moving said guide shaft

means away from said record material in response to said print head being moved to and occupying said other end of said guide shaft means,

60 said control means including a control lever, a latching lever for locking said control lever in the rotated position and cam means on said driving means for deactivating said latching lever in response to said print head being moved to and occupying said one end of said guide shaft means.

8. In a printer for printing electrically on electro-sensitive record material by means of a print head traversing said record material in a continuous movement in a reciprocating manner,

14

print head means including a print head,

guide shaft means for supporting said print head adjacent said record material for movement thereof across the width of said material, driving means for driving said print head from one end of said guide shaft means to the other at an essentially constant rate,

motor means for energizing said driving means, clutch means and actuating means therefor for connecting said motor means to said driving means in response to a control signal,

said guide shaft means being mounted eccentrically for movement with respect to said record material in response to rotation thereof,

control means for automatically moving said guide shaft means away from said record material in response to said print head being moved to and occupying said other end of said guide shaft means, said print head being freely rotatably mounted on said guide shaft means, and guide means secured to said print head for retaining said print head in a given disposition with respect to said record material, said guide means including a guide member having a slot in spaced parallel relationship with said guide shaft means and a guide bar having one end thereof secured to said print head and the other end thereof riding in said slot.

9. In a printer for printing electrically on electro-sensitive record material by means of a print head traversing said record material in a continuous movement in a reciprocating manner,

print head means including a print head, guide shaft means for supporting said print head adjacent said record material for movement thereof across the width of said material,

driving means for driving said print head from one end of said guide shaft means to the other at an essentially constant rate,

motor means for energizing said driving means, clutch means and actuating means therefor for connecting said motor means to said driving means in response to a control signal,

said driving means including a guide belt means secured to said print head and pulley means supporting said guide belt means for rotation, said driving means further including means for biasing said pulley means and said print head into a neutral position under conditions where said driving means is not driving said print head, said print head being disposed at said one end of said guide shaft when said neutral position is effected, and

detent means for positively determining said neutral position of said pulley means.

10. In a printer as set forth in claim 9 wherein said guide shaft means is mounted eccentrically for movement with respect to said record material in response to rotation thereof,

and including control means for automatically moving said guide shaft means away from said record material in response to said print head being moved to and occupying said other end of said guide shaft means,

means for deactivating said clutch means automatically in response to said print head being moved to and occupying said other end of said guide shaft means, said clutch means including a driven element, a driving element secured to said pulley means concentric with said driven element, a spring element secured to said driven element and encompassing a portion of said driving element, and means for selectively fixing said spring element with respect to said driven element in response to said actuating means,

said actuating means including electromagnet means for actuating said means for selectively fixing said spring element,

15

said means for deactivating said clutch means including cam means secured to said pulley means for deactivating said means for selectively fixing said spring element,

said control means including a control lever, a latching lever for locking said control lever in the rotated position and cam means on said pulley means for deactivating said latching lever in response to said print head being moved to and occupying said one end of said guide shaft means,

said print head being freely rotatably mounted on said guide shaft means, and guide means secured to said print head for retaining said print head in a given disposition with respect to said record material, said guide means including a guide member having a slot in spaced parallel relationship with said guide shaft means and a guide bar having one end thereof secured to said print head and the other end thereof riding in said slot.

11. In a printer for printing electrically on electro-sensitive record material by means of a print head traversing said record material in a continuous movement in a reciprocating manner,

print head means including a print head, a cylindrical platen for accommodating the record material, a guide shaft for slidably supporting said print head, means for mounting said guide shaft parallel to said platen and adapted to permit engagement between said print head and the record material during an excursion across the width of said material, timing belt means secured to said print head for driving said print head and including a driving pulley and a driven pulley and an endless belt supported by said pulleys in parallel relationship with said shaft, motor drive means for driving said driving pulley at an essentially constant rate, said driving pulley being normally disconnected therefrom,

clutch control means for selectively connecting said motor drive means to said driving pulley in response to a control signal,

said clutch control means including spring clutch means for connecting said motor drive means to said driving pulley when actuated, and actuating means for actuating said spring clutch means in response to said control signal, and means for driving said print head in a return excursion along said shaft when said driving pulley is disconnected from said motor drive means.

12. In a printer as set forth in claim 11 wherein said mounting means includes eccentric support means for said shaft adapted for rotation to move said shaft and print head about an axis parallel to the record material, and

said print head is freely rotatably mounted on said guide shaft, and including guide means secured to said head for maintaining said print head in a given disposition with respect to said record material.

13. In a printer for printing electrically on electro-sensitive record material by means of a print head traversing said record material in a continuous movement in a reciprocating manner,

print head means including a print head, guide shaft means for guiding said print head adjacent said record material, during movement thereof across the width of said material,

timing belt means secured to said print head for driving said print head at an essentially constant rate including a driving pulley and a driven pulley and an endless belt supported by said pulleys,

motor drive means for driving said driving pulley being normally disconnected therefrom, clutch control means for selectively connecting said motor drive means to said driving pulley in response to a control signal,

said guide shaft means including eccentric support

means and a guide shaft supported by said eccentric support means for conjoint movement of said shaft and print head with respect to the record material, said print head being freely rotatably mounted on said guide shaft, and guide means secured to said print head for maintaining said print head in a given disposition with respect to said record material, said guide means including a guide member having a slot in spaced parallel relationship with said guide shaft means and a guide bar having one end thereof secured to said print head and the other end thereof riding in said slot.

14. In a printer as set forth in claim 13 and including control linkage means for actuating said eccentric support means to retract said print head automatically in response to said print head reaching a predetermined position along said guide shaft.

15. In a printer for printing electrically on electro-sensitive record material by means of a print head traversing said record material in a continuous movement in a reciprocating manner,

print head means including a print head, guide shaft means for guiding said print head adjacent said record material during movement thereof across the width of said material,

timing belt means secured to said print head for driving said print head at an essentially constant rate including a driving pulley and a driven pulley and an endless belt supported by said pulleys,

motor drive means for driving said driving pulley being normally disconnected therefrom, clutch control means for selectively connecting said motor drive means to said driving pulley in response to a control signal,

said clutch control means including spring clutch means for connecting said motor drive means to said driving pulley when actuated, and actuating means for actuating said spring clutch means in response to said control signal,

said actuating means including a spring actuating member normally latched in an inoperative position and control means for selectively releasing said spring actuating member in response to said control signal, said timing belt means including means for latching said spring actuating member in said inoperative position after one complete rotation of said driving pulley, the circumference of said driving pulley being equal to the length of the path of movement of said print head such that one complete rotation of said pulley produces one complete scan of said print head.

16. In a printer as set forth in claim 15 and including bias means associated with said driven pulley for biasing said pulley in a given position wherein said print head is in its start position such that rotation of said driven pulley must be effected against the bias of said spring means,

said guide shaft means including eccentric support means and a guide shaft supported by said eccentric support means for conjoint movement of said shaft and print head with respect to the record material, said print head being freely rotatably mounted on said guide shaft, and guide means secured to said print head for maintaining said print head in a given disposition with respect to said record material,

said guide means including a guide member having a slot in spaced parallel relationship with said guide shaft means, and a guide bar having one end thereof secured to said print head and the other end thereof riding in said slot,

detent means for positively determining the position of said driven pulley corresponding to the start position of said print head,

control linkage means for actuating said eccentric support means to retract said print head automatically in

response to said print head reaching a predetermined position along said guide shaft.
